ABSTRACT OF THE DISCLOSURE

Novel therapeutic compositions containing raubasine and a method of using the same in the treatment of venous diseases, including thrombosis, varicosis, non-cardiac edema, ulcus cruris varicosum and peripheral circulatory disturbances.

The instant invention relates to therapeutic compositions containing the alkaloid raubasine, which is also known as ajmalicine, δ -yohimbine and tetrahydroserptine and methods of using the same for the treatment of peripheral circulatory disturbances and particularly for the treatment of venous diseases.

The new methods of use and dosage of raubasine as disclosed herein depend upon a previously unknown and surprising mechanism of the action of this alkaloid. The present invention is also concerned with new pharmaceutical compositions in dosage unit form containing raubasine as active ingredient.

It is known that raubasine acts to reduce the resistance of the arterioles (Kroneberg, Arch. f. exper. Path. and Pharm., 233, 72/1958). Because of this effect, raubasine is used in the therapy of high arterial pressure in which the arterial resistance of all regions of the vessels is increased (Bachmann, Arzneimittelforsch., 10, 813/1960; Heintz and Losse, Dtsch. med. Wschr., 79, 1448/1954; and Thiele, Md. Wschr., 11, 645/1957). Furthermore, for this reason, raubasine has also been recommended for use in the therapy of peripheral circulatory disturbances (Lian, La Presse Medicale, 65, (66), 1477/1957; Dorst and Delange, La Vie Medicale, Medecine Therapeutique, No. 46/1965; Perrin, Gazette Medicale de France, No. 7/1965; and Pluvinage, ibid. No. 22/1965).

In connection with the above-mentioned therapeutic purposes, raubasine has been administered orally in the form of tablets at a dosage level of from 1 to at the most 5 mg. Higher dosages have, apparently, been avoided because raubasine was considered to be a purely general arterial vasodilator. However, for the therapy of peripheral circulatory disturbances, a general arterial vasodilator is of no or only doubtful value. In the case of circulatory disturbances, the arterial resistance is only increased in a limited region of the vessels. Through a dilation of all of the vessels, the blood is, in particular, passed through the healthy regions of vessels which are able to dilate to a much greater extent than are the diseased ones. The blood pressure thereby drops so that the diseased regions of the vessels are, following the administration of an arterial vasodilator, more poorly supplied with fresh

2

blood than previously (Hess, "Die obliterierenden Gefässerkrankungen," pub. Urban and Schwartzenberg, 1959).

In accordance with the invention it has now, surprisingly, been found that the administration of raubasine effects an increase in the tone of the veins although it reduces that of the arteries and that, even in the case of comparatively large doses, the feared drop in the blood pressure, which impairs the blood supply to the diseased organs, does not take place.

10 This effect can be explained by the fact that the constriction of the capacitative vessels mobilizes the blood depot and the increased supply of blood to the heart increases the heart minute volume. However, the increased heart minute volume compensates the peripheral arterial 15 vessel dilation and thereby prevents a drop in the blood pressure.

In experiments carried out on non-anaesthetized dogs and also on healthy human volunteers, it has now been found that the increase of the heart time volume and the 20 decrease of the vessel resistance are balanced to such an extent that the mean arterial pressure does not decrease. As a result, a deterioration of the blood supply to organs having diseased vessels is avoided. It is ensured by this 25 novel action of raubasine that the region supplied by the diseased vessels also profits from the increased blood circulation corresponding to the still available vessel reserve. Consequently, raubasine is superior to a pure vasodilator in the therapy of blood circulatory disturbances. The 30 above-mentioned increase of tone of the veins is also indicative that raubasine is of value as a medicament in the treatment of conditions in which the venous system is itself diseased, as, for example, thrombosis prophylaxis, varicose prophylaxis, ulcus cruris varicosum and the therapy of edemas of non-cardiac origin.

35 Therefore, one of the new methods of use, according to the present invention, utilizing the alkaloid raubasine is in the treatment of peripheral blood circulatory disturbances utilizing orally the raubasine in dosage of at least 10 mg. per day and preferably of more than 30 mg. per 40 day. Furthermore, in accordance with the invention it has been found that, in the case of peripheral blood circulatory disturbances, raubasine can also be administered intravenously, intra-arterially or intramuscularly. In the 45 aforesaid blood circulatory disturbances, dosages of 10 to 40 mg. of raubasine per day have, in general, proved to be very useful. In particularly difficult cases, such as, for example, involving arterial embolism, the dosage of raubasine can be further increased to 100–200 mg. (intravenous infusion within a period of 18 hours) without 50 toward results.

Thus, according to the present invention, there are also provided therapeutic compositions, comprising raubasine in admixture with a sterile, liquid injectable pharmaceutical carrier therefor or in admixture with a solid, or liquid, orally administerable pharmaceutical carrier therefor and in the form of a dosage unit containing at least 10 mg. 55 raubasine.

The preferred liquid carrier is water which may contain the conventional additives employed for injectable 60 solutions, such as stabilizers, solubilizers and buffers. Additives of this type include tartrate and citrate buffers, ethanol, complex-forming agents, such as ethylenediamine-tetraacetic acid and its nontoxic salts, and high

molecular weight polymers, such as liquid polyethylene oxide, for viscosity adjustment.

The raubasine can also be administered orally in the form of a liquid, as, for example, in the form of a syrup containing the conventional additives such as stabilizers, flavoring agents, colorants, solubilizers, buffering agents, etc. In this connection, the syrups are preferably aqueous in nature but need not be so. It is also possible to provide the raubasine in the form of a highly concentrated solution or dispersion thereof in suitably prepared capsules.

The raubasine can also be administered in the form of tablets, capsules, powders, dragees and other like forms intended for oral administration. In this connection, the raubasine is provided in admixture with a solid pharmaceutical carrier.

As examples of solid pharmaceutical carriers, there may be mentioned starch, lactose, mannitol, methyl cellulose, talc, highly-dispersed silicic acid, high molecular weight fatty acid, such as stearic acid, gelatine, agar agar, calcium phosphate, magnesium stearate, animal and vegetable fats and solid high molecular weight polymers, such as the polyethylene glycols. Such compositions intended for oral administration can, if desired, also contain a flavoring and/or sweetening agent.

Because raubasine is somewhat sensitive to light, i.e., it becomes brown colored after a time, compositions containing raubasine should be formulated and/or packaged so that this phenomenon is avoided. This difficulty can be overcome either by providing the compositions in brown glass tubes or, in the case of solid compositions, by making them in the form of dragees whereby each dosage unit has its own protection against light.

The following example is given as illustrative of an injection solution within the scope of the invention:

Raubasine	mg	10.00
Tartaric acid	mg	10.00
Citric acid	mg	12.25
Spirit	mg	32.00
Liquid polyethylene oxide (M.W. about 400; "Lutrol 9")	mg	200.00
Disodium salt of ethylene-diamine-tetraacetic acid ("Titriplex III")	mg	0.20
Sodium metabisulfite	mg	0.50
Sodium hydroxide	mg	1.63
Distilled water	ml	3.00

In order to provide a combined systematic action with an especially intensive local vasodilation, up to 3 ampoules (30 mg.) of raubasine can be injected intra-arterially into the femoral artery. In this case, there is obtained an especially marked increase of circulation in the muscle and skin of the diseased organ.

The following is given as illustrative of a therapeutic composition in accordance with the invention adapted for oral administration and constituting tablets of the following composition:

	Mg.	
Raubasine	10.00	
Starch	30.00	
Lactose	30.00	
Talc	6.00	
Magnesium stearate	0.20	
Agar agar	3.80	

For a prolonged treatment, 3-4 tablets in the form of dragees are given.

In carrying out clinical investigations with raubasine, the following effects were, in particular, observed:

(1) Patients presenting obstructed conditions due to venous diseases evidenced, following raubasine therapy, an almost complete regression of the edema which, when application of the raubasine therapy is interrupted, again

increases and again regresses upon the renewed administration of raubasine.

(2) Patients presenting obstructed conditions due to diseases of the venous system evidenced, following administration of raubasine, an almost complete regression of the obstruction so that wearing of elastic stockings was no longer necessary.

(3) A patient suffering from *ulcus cruris varicosum* had his condition favorably influenced by raubasine. The ulcers with which he was affected were healed as a result of treatment with raubasine.

(4) In a number of patients having various types of fractures, the edema associated with such fractures was dispersed more quickly when the patient was simultaneously treated with raubasine than in those instances where no raubasine therapy was employed.

(5) Patients affected with malignant tumors who, in a post-operative state, exhibit a pronounced edematous condition, evidenced a remarkable dispersion of this edema and a regression of localized swelling following treatment with raubasine.

These results were obtained by treating with good success more than 5,000 persons.

From the above clinical results, the following new uses for raubasine are indicated:

(1) Thrombosis prophylaxis:

Raubasine leads to an acceleration of the circulation.

(2) Varicose prophylaxis:

The increase of venous tone counters the formation of varicoses. Increased flow in the dilated veins is obtained. Therefore, the passive dilation stimulus, which inevitably leads to the formation or strengthening of varicoses, is absent.

(3) *Ulcus cruris varicosum*:

(35) As a result of the acceleration of the flow and increased tone in the venous circulation region, the edema associated with this condition is dispersed. Thereby, there results an improved circulation in the tissue, which avoids the formation of *ulcera crura* or promotes healing of any already existent ulcers.

(4) Therapy of edemas of non-cardiac origin:

In the cases of conditions following fractures, after venous thromboses, tumors and other venous-occasioned impairments of flow, there results the opening of venules due to the increased venous tone in comparison with the tissue pressure. As a result, there is produced, together with the overall effect of the raubasine, an increased circulation with acceleration of the flow and dispersion of the edema.

(50) The action of raubasine on the venous tone and on the whole circulation was determined and evaluated by the following experiments carried out on dogs and healthy human volunteers:

(55) (1) Experiments with narcotized dogs

In 5 cross-bred dogs having a weight of 9-14 kg., there were measured synchronously and recorded, maintained in a state of morphine-butallylonal narcosis, the arterial pressure in the aorta, the central venous pressure (at the height of the right ventricle) and the peripheral venous pressure in one of the femoral veins by means of electrical pressure transformers; the arterial flow-time volumes in the aorta abdominalis above the iliac fork and the venous flow-time volumes in a vena cava caudalis shortly above the junction of the iliacal veins was determined by means of electromagnetic flow probes. A high chronological resolving power permitted the determination of the interesting circulation parameters at intervals of 10 seconds. In the aforesaid experiments, raubasine, in the forms of its phosphate, was dissolved in 5.5% aqueous glucose solution, with the addition of 5% dimethyl formamide. 2 mg./kg. raubasine, as base, were injected intravenously.

(70) 75

The results which were obtained are summarized in the following Table 1 which follows:

Circulatory Parameters	Control values	Seconds after i.v. injection of 2.0 mg./kg. raubasine						
		10	20	30	40	50	60	120
(1) $\bar{P}$ [mm. Hg]	96	102	101	99	94	97	95	92
(2) Fr_{cor} [min. $^{-1}$]	141			No 10 sec. measurements		126	156	
(3) $\dot{V}_a$ [ml. 10 sec. $^{-1}$]	46.5	56.5	68.0	73.0	70.0	66.2	62.3	65
(4) $\dot{V}_v$ [ml. 10 sec. $^{-1}$]	46.0	70.0	79.5	73.2	68.5	64.0	61.0	63.5
(5) $\bar{p}_{vv}$ [mm. H ₂ O]	+6	+12	+42	+30	+19	+14	+13	+6
(6) $\bar{p}_{vp}$ [mm. H ₂ O]	+7	+50	+46	+35	+20	+13	+14	+12
(7) $\dot{V}_v - \dot{V}_a$ [ml. 10 sec. $^{-1}$]	-0.5	+13.5	+11.5	+0.2	-1.5	-2.2	-1.3	-1.5
(8) $\bar{p}_{vp} - \bar{p}_{vv}$ [mm. H ₂ O]	+1	+38	+4	+5	+1	-1	+1	+

NOTE.—(1) p_a =mean arterial pressure in the aorta

(2) Fr_{cor} =heart rate

(3) $\dot{V}_a$ =blood flow in the aorta abdominalis

(4) $\dot{V}_v$ =blood flow in the vena cava caudalis

(5) $\bar{p}_{vv}$ =mean central venous pressure (right ventricle)

(6) $\bar{p}_{vp}$ =mean peripheral venous pressure in the vena femoralis

(7) $\dot{V}_v - \dot{V}_a$ =difference between venous outflow and arterial inflow

(8) $\bar{p}_{vp} - \bar{p}_{vv}$ =difference between peripheral and central venous pressure.

As can be seen from Table 1, only 10 seconds following the injection of raubasine, the arterial inflow and

vestigation of the volume elasticity coefficients before and 2 and 30 minutes after the intravenous injection of 2

mg./kg. raubasine. These experiments were carried out, the results obtained are set out in Table 2 which follows:

TABLE 2

	Minutes after iv. injection of 2.0 mg./kg. raubasine					
	Control		2		30	
	Before occlusion	5 sec. after occlusion	Before occlusion	5 sec. after occlusion	Before occlusion	5 sec. after occlusion
(1) $\bar{p}_{vp}$ [mm. H ₂ O]	+5	+28	+7	+358	+3	+41
(2) Δp_{vp} [mm. H ₂ O]	+23		+51		+38	
(3) ΔVol [ml. 5 sec. $^{-1}$]	24		37		33	
(4) E_{ven} [mm. H ₂ O 5 sec./ml.]	0.96		1.38		1.15	

NOTE.—(1) $\bar{p}_{vp}$ =mean peripheral venous pressure before and 5 seconds after venous occlusion

(2) Δp_{vp} =increase of peripheral venous pressure within 5 seconds

(3) ΔVol =increase of volume in 5 seconds

(4) E_{ven} =elasticity coefficient of the peripheral veins defined as $\Delta p/\Delta Vol$.

the venous outflow had increased. However, this increase in circulation demonstrates, arterially and venously, a clearly different course, as the difference between venous outflow and arterial inflow clearly shows (line 7 of Table 1). For up to 20 seconds following injection, the venous outflow was greater than the arterial inflow. When the values for the pressure difference between the peripheral and central venous pressures are compared, then it can be seen that, synchronously with the relatively higher venous outflow, the peripheral venous pressure has also increased more markedly than the central venous pressure (line 8 of Table 1). Such a rapidly commencing increase of the peripheral venous pressure is to be attributed to a constriction of the capacitative vessels, i.e., to an increase of venous tone. This mechanism brings about a primary mobilization and displacement of blood from the capacitative vessels in the direction of lower venous pressure, i.e., in the direction of the heart, which then increases its output volume corresponding to the increased supply. Only in the second place does there take place an adaptive dilation of the arterial resistance vessels caused by the direct action of the raubasine. However, in the case of the primarily increased blood time volume, a decrease of the arterial pressure does not result.

The venous tone or the expansion resistance of the vessel wall is proportional to the pressure increase and inversely proportional to the volume increase per unit time and can be mathematically defined as the volume elasticity coefficient E_{ven} given by the equation:

$$\frac{\Delta P_{ven}}{\Delta vol} \cdot \text{time}$$

The above-described experimental procedure allowed for, by temporary occlusion of the flow-off veins, an in-

crease in the expansion resistance, i.e., the venous tone, increased by the action of the alkaloid raubasine and that this increase could still be detected 30 minutes following injection thereof.

45 (2) Experiments with non-anaesthetized dogs and healthy human volunteers

In studies using non-anaesthetized dogs, the heart minute volume was continuously measured in the aorta 50 ascends by means of chronically implanted electro-magnetic flow probes. The procedure followed in carrying out the flow measurement was that of Kolin and Kado (Proc. Nat. Acad. Sci., 45, 1313/1959) as well as of Khouri and Gregg (J. appl. Physiol., 18, 224/1963) and involved the 55 use of flow probes as manufactured by the firm of Biotronex Inc. As the calibration of the flow probe on non-anaesthetized animals is very difficult to carry out, the heart minute volume and the values dependent thereon, such as the beat volume and the peripheral resistance, are 60 expressed as a percentage of the initial values.

For the measurement of arterial blood pressure, catheters were chronically implanted in the aorta. The mean arterial pressure values were indicated by a Statham strain gauge type P 23 Db.

65 In order to obtain values for the registration of the central venous pressure, catheters were inserted from the vena jugularis up to the height of the heart and first allowed to heal in situ.

In obtaining values for the human volunteers, the blood 70 pressure was measured on the upper arm by the method of Riva-Rocci and the heart minute volume by the method of Wezler and Boger (Naunyl-Schmiedeberg's Arch. exp. Path. und Pharmak., 184, 482/1937).

In Table 3, which follows, there are summarized the 75 results of the experiments on non-anaesthetized dogs fol-

lowing the intravenous injection of 5.0 mg./kg. raubasine and in FIGS. 1 and 2 of the accompanying drawings there are compared the circulatory analyses on dogs and humans, respectively. In the case of dogs, during the first minutes following the injection of raubasine several analyses were carried out at short intervals of time. In this first phase of the action of the raubasine, there was obtained a considerable increase in the heart minute volume with the preponderant participation of the heart beat volume, whereas the heart rate increased only slightly. Synchronously with this first increase of the heart minute volume, there was observed a remarkable increase of the pressure in the right ventricle.

In the case of humans, 20 mg. raubasine were administered intravenously and circulatory analyses carried out over comparatively large intervals of time. The results were, in principle, the same as in the case of dogs. The blood pressure did not drop. Corresponding to the increased beat volume, there was only observed an increase of the blood pressure amplitude, 3 minutes following the injection. The central venous pressure was admittedly not measured, but, having regard to the constant mean arterial pressure, it can be safely assumed, within the limits of probability, that, in the case of man, too, the increase of the heart minute volume is the result of an increased blood supply.

TABLE 3

Circulatory parameters	Control Values	Seconds after injection			Minutes after injection		
		20	40	60	10	20	30
(1) $\bar{P}_a$ [mm. Hg]-----	98	96	100	98	95	97	108
(2) F_{cor} [min. ⁻¹]-----	135	148	142	146	130	142	136
(3) $\dot{V}_{aor}$ [Percent]-----	100	158	119	132	138	134	136
(4) V_{cor} [Percent]-----	100	145	114	122	142	128	134
(5) W [Percent]-----	100	62	86	75	70	73	81
(6) $\bar{P}_{alt. dextr.}$ [cm. H ₂ O]-----	+0.2	+4.9	+4.0	+2.7	+0.7	+0	+1.1

Note.—(1) $\bar{P}_a$ = mean arterial pressure
 (2) F_{cor} = heart rate
 (3) $\dot{V}_{aor}$ = heart minute volume
 (4) V_{cor} = heart beat volume
 (5) W = peripheral vessel resistance
 (6) $\bar{P}_{alt. dextr.}$ = pressure in right ventricle.

In FIG. 1, there are graphically shown the mean results obtained from 16 experiments on non-anaesthetized dogs following the intravenous injection of 5 mg./kg. raubasine and in FIG. 2 there are graphically shown the mean results obtained from 15 experiments on human volunteers following the intravenous injection of 20 mg. raubasine. In these two figures, the following abbreviations have been used:

P =blood pressure in mm. Hg
 F_{cor} =heart rate
 V_{aor} =cardiac output
 W =peripheral vascular resistance
 $P_{atr. dextr.}$ =central venous pressure
 V_{cor} =heart beat volume
 P_s/P_d =systolic/diastolic pressure in mm. Hg

If there is taken into account the stability of the mean arterial pressure, the absence of a clear increase in heart rate and the brief increase of the venous pressure, then the increase of the heart minute volume is primarily a result of the depot blood mobilized on the venous side of the circulation and made available to the heart. Consequently, the reduction of the peripheral resistance takes place predominantly pressure passively.

After passing through a short counter-regulatory phase, a relatively stable circulatory position is reached, the characteristics of which are the increased heart minute volume with reduced peripheral vessel resistance and unchanged arterial pressure values.

The increase of the blood time volume as a result of an increased venous supply clearly distinguishes raubasine from the large number of so-called vasodilators, insofar as a justifiably feared blood pressure reduction does not occur and thus optimum conditions are provided for the promotion of a pathologically reduced blood circulation.

What is claimed is:

1. A method of treating a human subject afflicted with a venous disease selected from the group consisting of venous thromboses, venous varicoses, non-cardiac edemas, cruris varicosum and peripheral venous circulatory disturbances which comprises administering to said subject raubasine in an amount of from 10 to 200 mg.

2. A method according to claim 1 which comprises administering said raubasine in an amount of from 10 to 30 mg. per day.

3. A method according to claim 1 which comprises administering said raubasine in an amount of from 30 to 200 mg. per day.

4. A method according to claim 1 in which the venous disease is venous thrombosis.

5. Method according to claim 1 in which the venous disease is venous varicosis.

6. Method according to claim 1 in which the venous disease is non-cardiac edema.

7. Method according to claim 1 in which the disease is ulcus cruris varicosum.

8. A method according to claim 1 in which the venous disease is arterial embolism and said raubasine is administered daily in an amount of from 100 to 200 mg. by intravenous infusion within a period of 18 hours.
